UNITED STATES PATENT OFFICE.

ALBERT O. ROOD, OF SYRACUSE, ASSIGNOR TO VINCENT P. TRAVERS, OF NEW YORK, N. Y.

HAMMOCK.

SPECIFICATION forming part of Letters Patent No. 269,542, dated December 26, 1882.

Application filed May 5, 1882. (No model.)

To all whom it may concern:

Be it known that I, ALBERT O. ROOD, of Syracuse, in the county of Onondaga and State of New York, have invented an Improvement 5 in Hammocks, of which the following is a specification.

Figure 1 represents a plan view of part of an ordinary hammock. Fig. 2 is a plan view of a corresponding part of my improved hammock.

The object of this invention is to improve the selvage of loosely-woven hammocks, such as those known as "Mexican hammocks." In Mexican hammocks, of which a portion is illustrated in Fig. 1, the selvage strands or cords $a a a^2$ are at intervals looped or interlocked to form the eyes b , which eyes are in the selvage at the distances required for holding the body-threads of the hammocks; and, moreover, 15 the inner selvage strand or cord, which is marked a^2 in Fig. 1, is carried into the body of the hammock, and is not solely part of the selvage, so that it is clear that in the ordinary Mexican hammock the selvage must be prepared as part and parcel of the hammock itself, and cannot be produced as a separate article 20 of manufacture to be worked into a hammock of suitable kind.

The object of my invention is to prepare 25 for hammocks a selvage which can be made as an article of manufacture by itself, and which can be united or worked into a hammock of suitable kind, either one having wide meshes or one having closer meshes; and to 30 this end the invention consists in making the selvage for a hammock with separate end loops which do not have to be carried into the body of the hammock, and in making said selvage with loops or eyes set close together, so 35 that the main strands of the hammock-body can be spaced therein as occasion may require.

In Fig. 2 of the drawings, the letter A represents my improved selvage, which here is shown to be composed of series of strands $d d$,

that are braided together, forming closely-set 45 loops $e e$, in some of which the strands $f f$ of the hammock-body will find their support. At the ends of the selvage A the strands d are formed into loops h to receive the end cord, g , or other end connection. The selvage thus constructed 50 with end loops, h , and closely-set eyes $e e$ can be made in quantities and taken to the hammock-maker, who can then weave onto it a suitable hammock, either one having close meshes or one having wider meshes, or one 55 constructed of thicker or one of thinner cords. The cords f need not be worked into a reticulated pattern, as in Mexican hammocks, but may, with my selvage, be carried across from one selvage to the other, and thus the making of 60 hammocks is greatly facilitated by the use of this selvage. Only such of the eyes e of the selvage will be used for receiving cords f as will conform to the desired spacing of meshes, yet the many eyes e adapt the selvage for use 65 on every kind and style of hammock.

I do not limit myself to producing the selvage by braiding, as the loops e may be produced by weaving on a selvage having the closed end loops, h . Another advantage of this 70 selvage is that either side can be used as the inner side thereof, the loops e being on two sides.

I claim—

1. The selvage A for hammocks, said selvage having closed end loops, h , and closely-set eyes $e e$ between said end loops, substantially as and for the purpose described.

2. The braided selvage A, made with projecting end loops, h , and adapted to support 80 the cords f of the hammock-body in some only of the loops e , that are formed by the braid, substantially as shown and described.

ALBERT O. ROOD.
